UNITED STATES PATENT OFFICE.

EVALENA S. THOMAS, OF LINDENWOLD, NEW JERSEY.

DESIGN FOR A TILE.

SPECIFICATION forming part of Design No. 30,072, dated January 24, 1899.

Application filed December 29, 1898. Serial No. 700,665. Term of patent 7 years.

To all whom it may concern.

Be it known that I, EVALENA S. THOMAS, a citizen of the United States, residing at Lindenwold, Camden county, State of New Jersey, have invented and produced a certain new and original Design for a Tile, of which the following is a full, clear, and exact description, reference being had to the accompanying drawings, forming a part of this specification.

My invention relates to the external form or configuration of tiling employed in laying mosaic or other tiled surfaces; and it consists in making such blocks or tiles of a novel form or shape, the distinguishing characteristics of which are shown in the annexed drawings, in which—

Figure 1 is an elevation of my tile-block, and Fig. 2 a plan view thereof.

The tile shown is flat, with three curvilinear vertical sides, two of said sides *a* and *b* consisting of compound curves forming a concavo-convex outline, and being equal in size and curvature, while the third side *c* is also concavo-convex, but of larger curves, its vertical planular length being equal to the hypotenuse of a right angle drawn from the corners of the two equal sides.

I claim as new and of my invention—

The design for a tile substantially as shown and described.

In testimony whereof I have hereunto affixed my signature this 19th day of December, A. D. 1898.

EVALENA S. THOMAS.
